CLAIM

I claim the ornamental design for an antenna with bowtie sectors, as shown and described herein.

DESCRIPTION

FIG. 1 is a left side and front perspective view of my antenna with bowtie sectors;

FIG. 2 is a front view thereof;

FIG. 3 is a rear view thereof;

FIG. 4 is a right side view thereof;

FIG. 5 is a left side side view being a mirror image thereof;

FIG. 6 is a top view thereof; and,

FIG. 7 is a bottom view thereof.

The broken lines in the drawings showing portions of the article form no part of the claimed design.

1 Claim, 6 Drawing Sheets
